UNITED STATES PATENT OFFICE.

JONATHAN ED. MORRIS, OF HYDE PARK, ILLINOIS.

LETTER-BOX.

SPECIFICATION forming part of Letters Patent No. 402,535, dated April 30, 1889.

Application filed September 2, 1887. Serial No. 243,597. (No model.)

To all whom it may concern:

Be it known that I, JONATHAN ED. MORRIS, a citizen of the United States, residing in Hyde Park, in the county of Cook and State of Illinois, have invented certain new and useful Improvements in Mail-Boxes; and I hereby declare the following to be a full, clear, and exact description of my invention, such as will enable others skilled in the art to which it

10 appertains to make and use the same, reference being had to the accompanying drawings, and to the figures and letters of reference marked thereon, which form a part of this specification.

15 My invention relates to mail-boxes used on residences, flats, public buildings, and offices as a receptacle for mail-matter delivered by carrier; and my invention consists in two receptacles for mail-matter—one for periodicals, 20 the other for letters; also, in a small receptacle for visitors' cards, a receptacle or pocket to hold a card containing information for the carrier, a name-plate, and a slip or pocket to receive and hold "Not at Home" or "Will 25 Return" cards.

In the accompanying drawings, Figure 1 is a perspective of the mail-box closed, showing the visitors'-card receptacle, the receptacle or pocket for card for carrier's information, the 30 name-plate, and the "Not at Home" or "Will Return" card holder. Fig. 2 is a view of the mail-box open, showing the inner lower part of the periodical-receptacle and the inner part of the letter-receptacle with wire guard 35 to prevent letters from falling out when the mail-box is opened.

The periodical-receptacle A is a box with an oblong aperture, *a*, in its top for the purpose of receiving the mail-matter. Around 40 the edges of said aperture *a* there are walls raised, over which the lid *b* drops to protect contents of mail-box from rain, snow, or other injurious agencies. The lid *b* is made with flanges to come down over the raised walls 45 surrounding said aperture *a*, and said lid is hinged to the mail-box, as shown at *c c* in Fig. 2 on the letter-receptacle B, so that it will drop of its own weight over the opening *a*, and so that it may be easily raised while putting 50 anything into the box. The periodical-receptacle is so constructed that the front wall of said periodical-receptacle extends

downward only to the top of the letter-receptacle B. The remaining space is vacant and is closed by the letter-receptacle B, as shown 55 in Fig. 1. When said letter-receptacle B is open or swung back, as shown in Fig. 2, the lower part of said periodical-receptacle A is open, so that the contents may be easily withdrawn.

The receptacles for the postman's guide and visitors' cards D D' are two boxes of sufficient size to receive an ordinary-sized visiting-card, and may be made separate and attached to the mail-box, or may be cast with the box, and 60 may be open at the side or top, and may or may not have glass fronts, so that the contents may be seen without removal. Said postman's guide and visiting-card receptacles D D' may be made any size and shape desired, and may be provided with hinged covers to protect the cards from rain or snow. In the front wall of said periodical-receptacle A there may be, at any convenient place, an opening cut and a glass inserted into the 65 same, so that it can be readily seen without opening the mail-box whether it contains mail-matter or not. Said opening is shown at *e* in Fig. 2.

The letter-receptacle B is a box with an 80 aperture in its top, having the walls and lid constructed in the same manner and for the same purposes as described as being in the said periodical-receptacle, excepting that the aperture in the letter-receptacle should be 85 smaller than the aperture in said periodical-receptacle. Said letter-receptacle is open on the side next to the periodical-receptacle A, so that mail-matter may be taken readily and easily from it when opened or swung back, as 90 shown in Fig. 2. Said letter-receptacle B is hinged to the periodical-receptacle A, as shown at *d d'* in Fig. 2, so that it may be easily opened or closed, and is provided with a lock on the opposite side from said hinges to secure the 95 letter-receptacle B to the periodical-receptacle A, so that mail-matter placed in the mail-box will be secured against any person not having a key thereto. Said letter-receptacle is provided with a guard, E, made of small 100 wire, in the shape of a horseshoe or any suitable shape, and attached to said letter-receptacle at or near its base, for the purpose of preventing letters or other mail-matter from

falling out when the mail-box is opened. It is preferable to have coils in said guard, as shown in Fig. 2 at E' F², to allow said guard to spring more easily when mail-matter is being taken from the box.

5 The name-plate F, Fig. 1, is a narrow piece of metal or other suitable material, on which may be placed the name of the person owning the mail-box, and is attached to the mail-box by means of screws, bolts, or rivets.

10 The "Not at Home" or "Will Return" card holder H is so constructed that when it is secured to the mail-box there will be sufficient space between it and the wall of the mail-box 15 to which it is secured to insert a card of the desired size to contain a few short words of information. An oblong opening is made in said card-holder, so that when a card is placed in it the words written thereon may be seen 20 without removing the card.

What I claim as my invention is—

1. In mail-boxes designed to be used on residences, public buildings, and offices, the com-

bination of the receptacle for periodicals, provided with an opening through which they 25 may be introduced from the outside, and a receptacle for letters provided with an opening through which they may be introduced from the outside, said receptacles being hinged together and so constructed that one forms a 30 door to the other, openable to permit access to both the periodicals and the letters, substantially as described, and for the purpose set forth.

2. In mail-boxes having a periodical-receptacle and a receptacle for letters hinged together, so that one forms a door for the other, the combination, with the letter-receptacle, of the guard E, substantially as and for the purposes described.

35 In testimony whereof I affix my signature in the presence of two witnesses.

40 JONATHAN ED. MORRIS.
